UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ARTICLE-PRESENTING MEANS FOR SEWING-MACHINES.

1,239,676.

Specification of Letters Patent. Patented Sept. 11, 1917.

Application filed November 10, 1916. Serial No. 130,532.

To all whom it may concern:

Be it known that I, ALBERT H. DE VOE, a citizen of the United States, residing at Westfield, in the county of Union and State 5 of New Jersey, have invented certain new and useful Improvements in Article-Presenting Means for Sewing-Machines, of which the following is a specification, reference being had therein to the accompanying drawings.

This invention relates to an improvement in devices for attaching small articles, and it has for its object to provide simple and effective means for successive delivery of 15 such articles to the fastening means, such as the stitch-forming mechanism of a sewing machine. The invention is designed more particularly to provide means for producing automatically a tape composed of 20 overlying strips of fabric with interposed dress-weights preferably secured therein at predetermined intervals.

In its preferred form, the present improvement is embodied in a sewing machine 25 comprising stitch-forming mechanism and a work-support having edge-guides on opposite sides of the stitch-forming mechanism to afford a lower-strip guiding channel above which is disposed an upper strip 30 guide sustained by the presser-foot. Upon the work-support and in advance of the stitch-forming mechanism is preferably mounted a yieldingly sustained segmental runway having in its delivery end an article cavity open adjacent the stitching point above and in close proximity to which is sustained the lower end of an article holding magazine swinging in a path concentric with the axis of curvature of the 35 runway. Pivottally connected with the magazine is a spring-pressed pushing finger having a depending projection or spur adapted to engage the edge of an article deposited in said cavity of the runway to advance it into the range of action 40 of the stitch-forming mechanism intermediate the upper and lower strips of fabric delivered to the stitch-forming mechanism by the respective guides.

50 The upper end of the magazine is preferably flared to form a funnel into which are directed by a suitable chute articles delivered from a slowly rotating peripherally apertured hopper containing a supply of 55 such articles. The hopper preferably de-

rives its operative movements from a connection with the rocking support of the magazine.

In the accompanying drawings, Figure 1 is a front side elevation of a portion of a 60 sewing machine embodying the present improvement. Fig. 2 an end elevation and Fig. 3 a plan of the same. Fig. 4 is a perspective view representing the parts of the improvement adjacent the stitching point. Fig. 5 65 is an elevation similar to Fig. 2 but viewed from the opposite end of the machine, and with the bracket-arm and bed-plate in transverse section. Fig. 6 is a detail sectional view representing the hopper rotating 70 means. Fig. 7 is a perspective view of the under side of the presser-foot. Fig. 8 is a view representing a section of the weighted tape with one of its component strips raised at one end to expose the arrangement 75 of the parts.

The machine represented in the drawings is of the well-known Singer No. 41 class, comprising the bed-plate 1 and overhanging bracket-arm 2 in the head 3 of which is 80 journaled the reciprocating needle-bar 4 carrying in the present instance the multiple needle-clamp 5 provided with three needles 6 arranged in a line crosswise of the direction of feed.

85 Mounted in the head 3 rearward of the needle-bar is the presser-bar 7 having secured upon its lower end the shank 8 of the presser-foot whose foot-plate 9 contains the usual needle-holes 10. The presser-foot is provided in its lower face rearward of its forward end with a strip-guiding channel 11 within which is the deeper article-guiding channel 12. The foot-plate is provided above its forward notched end with the 90 arched guide-loop 13 over which the upper strip is led to the upturned end of the channel 11 in its passage to the stitching point.

95 Upon the bed-plate is secured the usual work-plate or support 14 which is provided with the laterally spaced edge-guides 15 having lateral extensions 16 secured in position by screws 17 and affording a strip-guiding channel directed toward and disposed in advance of the stitch-forming 100 mechanism. The work-plate 14 has adjacent its forward edge the guide-loop 18 in alinement with the strip-guiding channel to which it serves to direct the lower strip.

Secured upon the work-plate 14 by screws 19 is the arched foot 20 of an upwardly and forwardly projecting spring arm 21 having an offset portion 22 affording a raised seat 5 to which is secured by means of the screw 23 the upper end of a segmental raceway 24 having in its upper face adjacent the lower or delivery end the article-cavity 25 and having in its extremity the notch 26 10 adjacent the stitching point. Extending forwardly from the closed end of the cavity 25 is the pusher clearance groove 27.

Mounted upon a fulcrum-stud 28 sustained by the bracket-arm head 3 is the hub 29 of a rocker provided with a rearwardly extending arm 30 and a forwardly extending arm 31 channeled in its outer portion to receive the inturned portion 32 of a lateral extension 33. To the outer end of the extension 33 is adjustably secured by screws 34 a flange 35 of a split collar 36 sustaining in vertically adjustable position the tubular magazine or carrier 37 for the articles to be attached. The magazine 37 is inclined laterally to avoid as far as possible obstructing the operator's view of the stitching point, and is flared at its upper or receiving end to form a funnel 38 while terminating at its lower end at an inclination with its length to 30 conform closely with the upper face of the runway 24 over and longitudinally of which it reciprocates in performing its operative movements.

Near its lower end the magazine 37 has a 35 transverse lug 39 upon which is fulcrumed by means of the stud-screw 40 one end of the pusher-arm 41 whose body portion is curved to conform with the shape of the magazine and has at its free end the depending finger 42 provided with the depending spur or projection 43 adapted to enter the clearance groove 27 when the magazine is in retracted position as represented in the drawings. A spring 44 secured to the lug 39 at one end 45 and bearing at its free end upon the pusher-arm 41, causes the finger 42 to normally rest upon the bottom of the article cavity 25.

The rocker-arm 30 is provided with a stud 45 entering a face cam-groove 46 in the 50 gear-wheel 47 which is mounted upon a stud 48 sustained by the bracket-arm 2 and meshes with a driving pinion 49 mounted on the main-shaft 50 of the machine. The cam-groove 46 is preferably designed to 55 part to the rocker one oscillation for each five stitches, thereby causing the article feeding means to present an article to the stitch-forming and feeding devices at every fifth stitch, or in such other spacing as may be 60 determined upon.

Secured by a suitable angle-piece 51 to the head of the bracket-arm is a chute 52 whose mouth extends over the funnel-mouth 38, this chute being suitably flared and rounded 65 to embrace one side of the cylindrical drum

or hopper 53 having its front side open at the center and provided with an inwardly inclined flange 54, the closed rear side 55 being provided with the inwardly projecting boss 56 journaled upon the bearing stud 57 70 which is sustained by the bracket-plate 58 mounted upon the bracket-arm head 3. The periphery of the hopper 52 is provided at intervals with discharge apertures 59 of substantially the size of the contained supply of articles to be fastened which, in the agitation caused by the step-by-step rotation of the hopper, are caused to issue therefrom and pass through the chute into the magazine or carrier 37 for ultimate delivery 75 80 at the stitching point.

The wall 55 of the hopper has secured to its rearward side the ratchet-wheel 60 which is engaged by the spring-pressed holding pawl 61 sustained by the bracket-plate 58, 85 and by a spring-pressed actuating pawl 62 mounted upon a rock-lever 63 fulcrumed intermediate its ends at 64 upon the bracket-plate 58 and having its opposite end connected by means of the bent link 65 with an arm 66 extending from the hub 29 of the magazine sustaining rocker. In order to prevent overthrow of the hopper under the action of the pawl 62 induced by its described connections with the magazine-sustaining rocker, an arched drag-spring 67 is secured by screws 68 upon the bracket-plate 58, its free end resting upon the wall 55 of the hopper.

Fulcrumed upon the upper end of the 100 rock-lever 63 by means of the screw-pin 69 and spring-washer 70 is the handle-lever 71 having in its hub portion a peripheral notch 72 embracing the stop-pin 73 upon the rock-lever 63. By the means described the handle-lever is adapted to assume and frictionally maintain either of two extreme positions relative to the rock-lever 63, in a manner well-known. The handle-lever carries upon its rearward face a stud 74 whose head is apertured to receive one end of a wire spring 75 having its opposite end rigidly attached to the actuating pawl 62. When the handle-lever is in one of said extreme positions the spring 75 is caused in a manner well-known 110 to press the pawl 62 into operative engagement with the peripheral teeth of the ratchet-wheel 60 for normal actuation of the hopper; but when such lever is in its opposite extreme position the pawl will be 115 yielding maintained by said spring out of operative relation with the ratchet-wheel and the hopper will cease to perform its normal rotary movements.

In the use of the machine, a charge of articles, such as dress-weights *a* in disk form, is inserted through the open side of the hopper which may, if desired, be turned by hand to introduce a supply into the magazine. A lower tape *b*, preferably with inturned 125 130

edges exposed upon the upper side is introduced beneath the guide-loop 18 and between the edge-guides 15 and beneath the delivery end of the runway 24 into a position beneath the needles; and an upper tape *c* with edges similarly turned under is led downwardly from a suitable supply spool over the guide-loop 18, within the notch in the forward end of the presser-foot 10 and within the guide-channel therein, after which the presser-foot is lowered and the machine set in motion.

The first few stitches are preferably taken through the material to unite together along the margins the initial ends of the overlying strips, after which the magazine advances toward the stitching point and with it carries the pusher-finger 42 which moves the initial weight *a* forward within the carrier 25 and deposits it in the notch 26 of the runway and upon the lower strip with which and the upper strip it is drawn by the feeding mechanism beneath the central needle and thereby firmly stitched to and between the upper and lower strips, as represented in Fig. 8 wherein the central seam *d* is shown passing through both strips and the weights *a* and the side seams *e* passing through the marginal hemis of both strips. As the mouth of the magazine reaches extreme advance position above the closed end of the article carrier 25, which affords an article-detaining shoulder, a succeeding dress-weight drops into the latter, so that upon the retraction of the magazine the next dress-weight slides backward over that so deposited and the upper face of the runway, the spur 43 of the pusher-finger 42 riding up over the dress-weight so deposited and snapping over the opposite edge of the dress-weight and entering the clearance groove 27 provided for the purpose in readiness for the next article-presenting excursion.

45 The dress-weights are preferably made of a soft metal, such as lead, which may be penetrated by a needle in the stitching operation; but it is evident that they may be previously formed with apertures to receive the needles, in case they are made of harder metal, or the central line of stitches may be omitted entirely, the weights being laterally confined in position by the edge seams.

50 It is also evident that the component strips of the weighted tape may be selvaged and unhemmed, or that one or both may be replaced by a body fabric of the garment to which the weights are to be applied, the work-directing means being modified correspondingly to suit such conditions.

55 It is evident that the present improvement is susceptible of material modification in the construction and arrangement of its parts within the scope of the invention, which

latter is not to be understood as limited to the specific embodiment thereof herein shown and described.

Having thus set forth the nature of the invention, what I claim herein is:—

1. In a sewing machine, in combination, stitch-forming mechanism, a work-support, a reciprocatory open-bottomed article-carrying magazine, a runway affording a bottom for said magazine and having a detaining shoulder for engagement with each article as it is deposited on said runway, and a pusher moving with said magazine and adapted to engage an article upon said runway at the side thereof engaged by said shoulder for moving it beyond the end of the runway. 70

2. In a sewing machine, in combination, stitch-forming mechanism, a work-support, a reciprocatory open-bottomed article-carrying magazine, a runway sustained above and spaced from the work-support to afford a bottom for said magazine and having a detaining shoulder for engagement with each article as it is deposited on said runway, and a pusher moving with said magazine and adapted to engage an article upon said runway at the side thereof engaged by said shoulder for moving it beyond the end of the runway. 80

3. In a sewing machine, in combination, stitch-forming mechanism, a work-support, a reciprocatory open-bottomed article-carrying magazine, a spring-pressed runway affording a bottom for said magazine and having a detaining shoulder for engagement with each article as it is deposited on said runway, and a pusher moving with said magazine and adapted to engage an article upon said runway at the side thereof engaged by said shoulder for moving it beyond the end of the runway. 90

4. In a sewing machine, in combination, stitch-forming mechanism, a work-support, a reciprocatory open-bottomed article-carrying magazine, a runway, affording a bottom for said magazine, and means coöperating with said magazine for successively conveying the contained articles in plural-stage movements toward the stitch-forming mechanism. 100

5. In a sewing machine, in combination, stitch-forming mechanism, a work-support, a reciprocatory open-bottomed article-carrying magazine, a runway affording a bottom for said magazine, and means coöperating with and moving in unison with the magazine for successively conveying the contained article toward the stitch forming mechanism. 115

6. In a sewing machine, in combination, stitch-forming mechanism, a work-support, an edge-guide directed to one side of the stitch-forming mechanism, an upper strip-guide, and means for delivering at prede- 120

130

4
terminated intervals upon the work-support in advance of and in alinement with the stitch-forming mechanism a succession of articles to be embraced between the upper 5 strip and a lower fabric upon the work support.

7. In a sewing machine, in combination, 10 stitch-forming mechanism, an upper strip-guide, a lower strip-guide, and means for delivering articles in advance of the stitch-forming mechanism between overlying upper and lower strips embraced by the respective strip-guides.

8. In a sewing machine, in combination, 15 stitch-forming mechanism, an upper-strip-guide, a lower strip-guide, and means including a reciprocatory carrier for delivering articles successively between upper and lower strips embraced by the respective 20 strip-guides.

9. In a sewing machine, in combination, 25 stitch-forming mechanism, a work-support, an edge-guide directed to one side of the stitch-forming mechanism, an upper strip-guide, an article-carrier overhanging the work-support, and means for imparting to 30 said carrier reciprocatory movements toward and from the stitch-forming mechanism.

10. In a sewing machine, in combination, 35 stitch-forming mechanism, a work-support, an edge-guide directed to one side of the stitch-forming mechanism, an upper strip-guide, an article-carrier overhanging the work-support, means for imparting to 40 said carrier reciprocatory movements toward and from the stitch-forming mechanism, and a pusher coöperating with said carrier for successively conveying its contained articles toward the stitch-forming mechanism.

11. In a sewing machine, in combination, 45 stitch-forming and feeding mechanisms, a work-support, an open-bottomed article-carrying magazine, a rocker sustaining said magazine, an actuating cam, a connection between said cam and said rocker, a runway 50 sustained above and spaced from the work-support to afford a bottom for said magazine and having an article-detaining shoulder, and a pusher operatively connected with said rocker and adapted to engage an article upon said runway at the side thereof engaged by said shoulder for moving it beyond the end of the runway.

12. In a sewing machine, in combination, 55 stitch-forming and feeding mechanisms, a work-support, an open-bottomed article-carrying magazine, a rocker sustaining said magazine, an actuating cam, a connection 60 between said cam and said rocker, a yielding-supported runway sustained above and spaced from the work-support to afford a bottom for said magazine and having an article-detaining shoulder, and a pusher operatively connected with said rocker and

adapted to engage an article upon said runway at the side thereof engaged by said shoulder for moving it beyond the end of the runway in the direction of feed.

13. In a sewing machine, in combination, 70 stitch-forming and feeding mechanisms, a work-support, an open-bottomed article-carrying magazine, a rocker sustaining said magazine, an actuating cam, a connection between said cam and said rocker, a runway 75 sustained above and spaced from the work-support to afford a bottom for said magazine and having an article-detaining shoulder, and a spring-pressed pusher operatively connected with said rocker and adapted to 80 engage an article upon said runway at the side thereof engaged by said shoulder for moving it beyond the end of the runway in the direction of feed.

14. In a sewing machine, in combination, 85 stitch-forming and feeding mechanisms, a work-support, a reciprocatory open-bottomed article-carrying magazine, a runway affording a bottom for said magazine and having an article-detaining shoulder, a 90 spring-arm mounted upon the work-support and affording a yielding support for said runway, and a pusher coöperating with said magazine for conveying toward the stitch-forming mechanism articles deposited by the 95 magazine upon said runway.

15. In a sewing machine, in combination, 100 stitch-forming mechanism, a work-support, a reciprocatory open-bottomed article-carrying magazine, a runway directed toward said stitch-forming mechanism and affording a bottom for said magazine, means for conveying articles from the mouth of said magazine along the runway to stitching position, an article-supply hopper with means 105 for effecting the delivery of articles successively, and a chute adapted to convey to the magazine the articles so delivered.

16. In a sewing machine, in combination, 110 stitch-forming mechanism, a work-support, a reciprocatory open-bottomed article-carrying magazine, actuating means therefor, a runway directed toward said stitch-forming mechanism and affording a bottom for said magazine, means for conveying articles from the mouth of said magazine along the runway to stitching position, a rotary 115 article-supply hopper apertured for successive delivery of articles, means operatively connected with the magazine actuating 120 means for imparting operative movements to said hopper, and a chute adapted to convey to the magazine the articles so delivered.

17. In a sewing machine, in combination, 125 stitch-forming mechanism, a work-support, a reciprocatory article-carrying magazine movable toward and from the stitch-forming mechanism, an article-supply hopper with means for effecting the delivery of the 130 contained articles successively, and a chute

adapted to convey to the magazine the articles so delivered.

18. In a sewing machine, in combination, stitch-forming mechanism, a work-support, a reciprocatory article-carrying magazine movable toward and from the stitch-forming mechanism, actuating means therefor, a rotary article-supply hopper apertured for successive delivery of contained articles, operating means connected with the magazine, actuating means for imparting operative movements to said hopper, a throw-out device connected with said operating means for interrupting the operative movements of the hopper while said actuating means continue in action, and a chute adapted to convey to the magazine the articles so delivered. 15

In testimony whereof, I have signed my name to this specification.

ALBERT H. DE VOE.
